UNITED STATES PATENT OFFICE.

HARRY E. CAMPBELL, OF NEW YORK, N. Y.

APPARATUS FOR CLOSING WINDOW-SASHES.

1,238,642.

Specification of Letters Patent. Patented July 17, 1917.

Application filed November 13, 1916. Serial No. 131,062.

To all whom it may concern:

Be it known that I, HARRY E. CAMPBELL, a citizen of the United States, residing at New York, in the county of New York and State of New York, have invented a certain new and useful Improvement in Apparatus for Closing Window-Sashes, of which the following is a specification.

The invention is an apparatus for closing a window sash, or sashes, upon the attainment of a predetermined degree of temperature of the surrounding atmosphere, and for retaining said sash, or sashes, in closed position. As is well known, it is frequently desirable, in event of a fire occurring in an apartment or building, to close the windows in order to cut off access of air to the fire, and this, after the fire has started, it is often difficult or impossible to do. The present device operates automatically, and, as hereinafter set forth, is controlled by a destructible or fusible member, which upon rupture releases a weight which is suitably connected to the sash to close the same by reason of its descent, and the locking device is timed to engage said sash after it has reached the closed position.

In the accompanying drawings—

Figure 1 is an elevation of my window sash closer, showing the lintel of the window frame and a portion of one of the jambs and of the upper sash, with parts broken away to exhibit the internal construction—the closing device being set for operation with the sash open. Fig. 2 is a section on the line 2, 2, and Fig. 3 is a section on the line 3, 3, of Fig. 1. Fig. 4 is also a section similar to Fig. 3, but with the parts in the positions assumed after the release of the device—the sash then being closed and locked.

Similar letters and numbers of reference indicate like parts.

A is a box lintel of plate metal. B is the upper portion of a hollow jamb, the said lintel and jamb forming members of a metal window-frame of the type shown in U. S. Letters Patent No. 1,189,912, granted to me July 4, 1916. In the inner jamb wall are two vertical slots C, D, through which slots pass plates E laterally projecting from the side rails of each of the sashes F, G. Similar plates on the opposite side rails enter similar slots in the opposite jamb. Between said plates H and I having their facing edges

turned upward to form flanges J inclined toward one another. When the sash G is in raised position, an upwardly projecting plate K on the front member L of the sash frame enters between the flanges J, as shown in Fig. 4. The rear member M of said sash frame, which is united to said front member by welding or other suitable means, has a rearwardly projecting ledge N.

At each end of the lintel is a compartment formed by the two parallel transverse partitions O, P, and the partition Q formed by bending the partition P at right angles. As the partitions O, P, which extend from the rear vertical wall of the lintel, do not reach across said lintel, a space R therein remains in front of the partition Q. Journalled in the partitions O, P of each compartment is a suspension pulley S, over which pass the sash suspension chains, one of which is shown at T, Fig. 2. The ends of the chains are connected to ledges U, V, formed on the sash plates E within the jambs. In this way, the sashes mutually counterbalance one another, so that when one sash is lowered, the other is raised. On the upper rail of the lower sash are longitudinal mutually inclined flanges W, Fig. 3, which, when the sashes are closed, receive between them a longitudinal upwardly extending flange, not shown, on the bottom rail of the upper sash—thus closing the joint between the meeting rails of said sashes. The construction of the parts coöperating to form this meeting rail joint is not a part of my present invention.

Disposed within the lintel and journalled in the partitions P at each end thereof is a shaft 5. On said shaft is a fixed collar 6, on which is an arm 7, which is bent at right angles to extend into the lintel space R in front of partition Q. A weight 8 disposed in the hollow jamb B has an upwardly extending rod 9. Said rod is hooked at its upper end, as shown at 10, to engage the arm 7. A projection 11 on one side of the weight 8 extends over the ledge V on extension plate E of sash F. A second collar 12, also fast on shaft 5, has a latch arm 13, curved over at its extremity 14. Said arm passes through openings in the lintel bottom and plate H. There is an elongated opening 15 in collar 12 adapted to receive a wedge 16, which may be loosened to adjust the collar upon the shaft and after-

ward tightened to retain said collar in adjusted position. A bracket 17 on the under side of plate H carries one end of a fusible or destructible member 18, preferably of metal or alloy, the other end of said member engaging the extremity 14 of latch arm 13. I may make this member of two pieces united together, as shown in Fig. 3, or of a single piece. Any material may be chosen for the destructible member which will become fused or ruptured when the temperature surrounding the same reaches a predetermined point, under which condition it is desired the sashes shall be closed and locked. 15 On the under edge of latch arm 13 is a notch 19 which, when the upper sash is in the raised position shown in Fig. 4, engages the ledge N on said sash.

The operation of my device is as follows: 20 The arms 7 and 13 on shaft 5 are preferably placed at such an angle to one another as that when the latch arm 13 engages the destructible member 18, the arm 7 is horizontal, as shown in Fig. 3. The hooked end 25 10 of the weight rod 9 then extends over said arm 7, so that the weight 8 is suspended by said rod 9, and the shaft 5 is prevented from rotating by the engagement of arm 13 with said destructible member 18. Said member is, therefore, under the strain of 30 the weight 8. The sashes may now be both open, as shown in Fig. 3.

When the predetermined temperature is reached at which it is desired the sashes shall automatically close, the member 18 becomes ruptured. The arm 13 being released, the shaft 5 is free to be turned by the descent of weight 8. As the weight falls, (the hook 10 disengaging from the arm 7), 40 the projection 11 on said weight forces down the lower sash, and through the connecting suspension chains T the upper sash is correspondingly raised and closed, as shown in Fig. 4. When the upper sash reaches its desired closed position, the ledge N thereon is in position to be and is engaged by the notch 19 in latch arm 13. This locks the upper sash in place, so that it cannot drop by gravity, and so afford an air entrance. 45 Hence my device operates automatically upon the occurrence of a fire in the room into which the window opens, or the impact of flame from outside, or the production of a critical temperature in any other way, instantly to close the window sashes and lock the upper sash in closed position.

I claim:

1. A window-frame, a movable sash therein, means normally operating to move said sash into closed position, a latch for preventing the operation of said moving means, and means controlled by and operating upon a predetermined rise in temperature for releasing said latch.

65 2. A window-frame, a movable sash

therein, means normally operating to move said sash into closed position, a latch for preventing the operation of said moving means, and constructed to engage said sash, means controlled by and operating upon a predetermined rise in temperature for releasing said latch, and means for moving said released latch into engagement with said closed sash.

3. A window-frame, a vertically movable sash therein, a weight connected to said sash and operating by gravity to move said sash into closed position, a latch for holding said weight raised, and means controlled by and operating upon a predetermined rise of temperature to release said latch and permit the descent of said weight.

4. A window-frame, two vertically movable mutually counterbalanced sashes therein, suspension means for said sashes, a shaft journaled in said frame above said sashes, an arm on said shaft, a weight suspended on said arm and extending over the top rail of the lower sash, a latch arm on said shaft, and a member of material destructible at a predetermined temperature connected at its ends respectively to a fixed support and to said latch arm; whereby said weight is held in raised position until on the attainment of said predetermined temperature, said destructible member is destroyed, thereby releasing said latch arm and permitting said weight to move downwardly said lower sash, and through said suspension means to close said upper sash.

5. A window-frame, a vertically movable sash therein, a shaft journaled in said frame above said sash, a weight connected to said sash and normally operating by gravity to move said sash into closed position, an arm on said shaft, a vertical rod on said weight hooked at its upper end to engage said arm and suspension weight, a latch arm on said shaft, and a member of material destructible at a predetermined temperature connected to said frame and said latch arm; whereby said weight is held in raised position until on the attainment of said predetermined temperature, said destructible member is ruptured, thereby releasing said latch arm and permitting said weight to fall and close said sash.

6. A window-frame, comprising hollow jambs having vertical slots in their inner walls, and a box lintel, two mutually counterbalancing sashes slidable in said slots, suspension pulleys inclosed in said lintel, suspension chains within said jambs passing over said pulleys and connected at their ends to said sashes, a shaft in said lintel, an arm on said shaft, a weight in one of said jambs disposed above the lower sash and suspended from said arm, a latch arm on said shaft, and a member of material destructible at and by a predetermined rise in temperature.

connected at one end to said frame and at its other end engaging said latch arm; whereby upon the attainment of said predetermined temperature, said member shall be ruptured, thereby freeing said latch arm and said weight, and whereby said weight in falling causes the closing of both of said sashes.

7. A window-frame, a vertically slideable sash in said frame, a suspension device, and

10 a counter-weight for said sash, a second weight disposed above said counter-weight, releasable means for suspending said last-named weight, and means operating upon and controlled by a predetermined rise in temperature for releasing said second weight

15

to overbalance said sash and move the same into closed position.

8. A window-frame, a sash vertically slideable therein, a suspension device, means for counterbalancing said sash, and means operating upon and controlled by a predetermined rise in temperature for overbalancing said sash and thereby moving the same into closed position.

In testimony whereof I have affixed my 25 signature in presence of two witnesses.

HARRY E. CAMPBELL.
